UNITED STATES PATENT OFFICE.

FRANK J. MALIHA, OF WILMINGTON, DELAWARE.

TRIGGER-LOCKING DEVICE FOR AUTOMATIC TOOLS.

1,205,237.

Specification of Letters Patent. Patented Nov. 21, 1916.

Application filed April 19, 1916. Serial No. 92,267.

To all whom it may concern:

Be it known that I, FRANK J. MALIHA, a citizen of the United States, residing at Wilmington, in the county of New Castle 5 and State of Delaware, have invented certain new and useful Improvements in Trigger-Locking Devices for Automatic Tools, of which the following is a specification.

My invention consists of an improved device for preventing the accidental operation of automatic tools such for example as pneumatic riveting hammers where the tool point is loose within the hammer casing and is actuated by air pressure when a trigger is 15 moved.

Persons have often been injured by flying tool points which have been ejected from the hammer casing by an accidental movement of the actuating trigger, and it is one 20 of the objects of my invention to effectively prevent such an accidental movement of triggers on tools of the above described character.

Another object of my invention is to produce a device which may be quickly secured 25 to the handles of pneumatic tools now on the market.

A further object is to so construct said device that it will be durable and can be 30 manufactured at a small cost.

A still further object is to construct my invention that it may be easily operated to move it into an active or inactive position so as to either lock the trigger or permit the 35 trigger to be operated.

These objects and other advantageous ends which will be described hereinafter, I secure in the following manner reference being had to the accompanying drawing in 40 which—

Figure 1 is a perspective view showing a portion of a pneumatic hammer having my invention thereon. Fig. 2 is a plan view of Fig. 1, and Fig. 3 is a transverse sectional view taken on the line *a—a*, Fig. 2.

Referring to the drawings, 1 represents a handle of an automatic hammer and 2 is the actuating trigger thereof which is pivoted to the handle by a pivot pin 3. The handle 50 1 and the trigger 2 may be of any well known construction, and said trigger operates mechanism within the handle, and since this mechanism may be of any well known type and operative to control the 55 operating means within the handle, the same is not shown in the drawing, it being suffi-

cient to state that a downward movement of the trigger 1 causes the operation of the mechanism within the hammer.

Since the general contour of the handle 1 60 is rounded as shown in the several views of drawing, I provide a block 4 which forms a pivot support for a locking lever 5, there being a pivot pin 6 extending through said locking lever and secured within the block 65 4, so that the lever is free to move around said pivot pin. The block 4 is of such height that the bottom of the lever 5 is substantially in a plane with the top of the handle 1. The trigger 2 operates within a 70 slot 7 in the handle, and the handle is notched at 8 to receive the locking lever 5 when it is turned into position shown in the full line positions in the several views of drawing. The locking lever 5, by being so constructed, 75 will fit directly under the trigger 2, and preferably in engagement therewith, so that practically no movement of said trigger is permitted when the said lever 5 is thereunder.

The free end of the lever 5 is provided 80 with an upwardly extending projection 9 of such length that it facilitates the movement of the lever 5 out of the notch 8 by the operator. As a means for automatically moving 85 the lever 5 after it has been released from the notch, I provide a coiled tension spring 10. One end of this coiled spring is attached to a lug 11 adjacent the end 9 of lever 5, the other end of said spring being 90 secured by a screw 12 to the outer face 13 of the block 4. The arrangement of the parts is such that when the lever 5 is in its locking position under the trigger 2, the coiled spring 10 will be stretched across the 95 face 13 of the block 4 around the corner 14 of the latter, then in front of the face 15 of said block, and thereafter following the curved contour of the handle and extending across the slot 7, thereby causing the said 100 spring to be stretched in a curved form which facilitates the action of said spring in moving the lever 5 quickly and positively into the position shown in dot and dash lines in Fig. 1, since the normal position of 105 said spring is straight as shown in said dot and dash position shown in Fig. 1. Furthermore by this arrangement of the spring there is absolutely no chance for the lever 5 to swing backwardly after it has once started 110 its movement toward the dot and dash position as previously stated.

The operation of my invention is as follows: Considering that the lever 5 is in its position under the trigger 2 and within the notch 8, in order to start the operation of 5 the hammer, the operator merely presses the end 9 with sufficient force to move the lever out of its notch, said notch being sufficiently shallow to allow this movement. After the lever 5 has been so moved, the spring 10 10 which is under tension will automatically move the lever 5 on the pivot 6 into the position shown in dot and dash lines in Fig. 1. The trigger is then free to be moved downwardly by the operator to start the action 15 of the hammer. To lock the trigger, the lever 5 is manually turned under the trigger until it again is moved into the notch.

While I have shown and described my invention in connection with an automatic 20 hammer, it will be understood that it may be used with equal advantage any place where a movable trigger extends from a handle or the like, and where it is desired to prevent the accidental movement of said 25 trigger.

While I have described my invention as taking one particular form, it will be understood that the various parts of my invention may be changed without departing 30 from the spirit thereof, and hence I do not limit myself to the precise construction set forth, but consider that I am at liberty to make such changes and alterations as fairly come within the scope of the appended 35 claims.

Having thus described my invention, what I claim as new and desire to secure by Letters Patent is:

1. The combination of a handle, a trigger 40 movably mounted on said handle, a lever on said handle and movable between it and the trigger, means for holding said lever in said latter position, and automatic means for moving said lever from its position between 45 said trigger and handle after it has been manually released from said holding means, substantially as described.

2. The combination of a handle and a block projecting therefrom, said block having 50 lever-holding means thereon, a trigger movably mounted on said handle, a lever movably mounted on said block and movable between the handle and the trigger and into locking engagement with said holding 55 means, and a coiled spring bendable under tension around said block and secured to said lever, said spring being operative when said lever is released from said holding means to automatically move said lever from its position between said trigger and the handle, substantially as described.

3. The combination of a handle, a trigger 60 movably mounted on said handle, a lever pivoted on said handle and movable between it and the trigger, said handle being notched

transversely to said trigger to receive the lever after said movement to prevent the accidental movement of said trigger, substantially as described.

4. The combination of a handle, a trigger 70 movable in said handle, a lever pivoted on said handle and movable between it and the trigger, said handle being notched to receive the lever after said movement, and automatic means for moving said lever from its 75 position between the handle and trigger after the lever has been manually moved from the notch, substantially as described.

5. The combination of a handle, a block 80 projecting therefrom, a trigger movably mounted on said handle, a lever on said handle and movable between it and said trigger, means for retaining said lever between the trigger and the handle, and a spring secured to the lever and designed to be bent around 85 the block, said spring being operative to automatically move said lever from its position between the handle and the trigger after said lever has been manually released from the retaining means, substantially as 90 described.

6. The combination of a handle having a slot therein, and a notch extending transversely to said slot, a trigger on said handle and movable within said slot, said trigger 95 normally having a portion projecting beyond said handle, a lever pivoted to the handle and movable under said trigger and across said slot into said notch to lock said trigger against accidental movement, substantially as described.

7. The combination of a handle having a slot therein, a trigger pivoted to said handle and movable within said slot, said trigger normally having a portion projecting beyond said handle, a lever pivoted to the handle and movable under said trigger and across said slot, said handle having a notch into which said lever extends when under 105 said trigger to lock said trigger against accidental movement, substantially as described.

8. The combination of a handle having a slot therein, a trigger pivoted to said handle and movable within said slot, said trigger normally having a portion projecting beyond said handle, a lever pivoted to the handle and movable under said trigger and across said slot, and a coiled spring secured to said lever and to the handle for automatically moving said lever from under said 110 trigger, substantially as described.

9. The combination of a notched handle having a slot therein and a block thereon, a trigger pivoted to the handle and movable within said slot, said trigger normally having a portion extending out of said slot, a lever pivoted to said block and movable under said trigger and across said slot into the notch in the handle, and a coiled spring 115 having one end attached to said lever and

the other end attached to said block, said spring being under tension and turned around a corner of said block when the lever is in said position, said spring serving to 5 automatically move said lever from its said position into a position normally free of said trigger when the lever is moved out of said notch, substantially as described.

In testimony whereof I have signed my name to this specification in the presence of 10 two subscribing witnesses.

FRANK J. MALIHA.
